UNITED STATES PATENT OFFICE.

GEORGE W. BROWN, OF NEW YORK, N. Y.

SAFETY HOD-ELEVATOR.

SPECIFICATION forming part of Letters Patent No. 240,227, dated April 19, 1881

Application filed February 17, 1881. (No model.)

To all whom it may concern:

Be it known that I, GEORGE W. BROWN, of the city of New York, in the county and State of New York, have invented certain new and useful Improvements in Safety Hod-Elevators, of which the following is a specification.

The objects of my invention are to construct a hod-elevating apparatus with metallic tubular frames, which shall be consequently lighter, stronger, more durable, and cheaper than those now in use, which shall be safe to use, and which shall have sufficient tractive power, from the improved construction hereinafter described, to elevate materials in a continuous supply sufficient for the high buildings now common in large cities, without a corresponding increase in the tension and expenditure of power. These objects are attained by the mechanism illustrated in the accompanying drawings, in which—

Figure 1 represents a front elevation, and Fig. 2 represents a side elevation, of my improved safety hod-elevator, wherein similar letters of reference indicate corresponding parts. I construct the bottom frame, containing the driving machinery, of metallic tubes or pipes, cut into the required lengths and joined together in the desired form by the ordinary elbows and T's or suitable couplings, and thereby greatly increase the strength and durability of the frame, and at the same time make it lighter and more easily handled and more inexpensive than usual.

B B is the bottom of the frame, and A A uprights, connected at the top by a suitable plate strapped to the bottom by turn-buckles or equivalent means, to secure greater rigidity. Sliding between these uprights is a casting, L, fitted to hold and connect the boxes or bearings for two shafts, the lower carrying the actuating or driving pulleys I I and spur-gearing P P, and the upper carrying the pinion O and double ratchet-wheel having circumferentially two parallel series or sets of teeth, a c, pointing in opposite directions and respectively engaging the two pawls b d. One pawl is intended to be always in position to prevent the combined weight of the ascending loaded hods reversing motion, should the laborers turning the machine leave suddenly through fright, and the other pawl is intended

to be always ready to come into position and positively stop all ascending motion when the top hod reaches a certain height, and, by its ascending motion and a connecting string, 55 pulls it into position, as specified, claimed, and allowed in Letters Patent No. 149,636, hitherto granted to me.

The spur-gearing may be cast to the side of one of the actuating or driving pulleys, as 60 shown in Fig. 1, or may be the ordinary wheel gearing with the pinion in the usual manner. The two actuating or driving pulleys I I are constructed with a sufficiently-deep circumferential groove having alternate projections, and 65 preferably corresponding recessions opposite, upon each cheek, thus forming an undulated channel, which obliges the cable going over the pulley to take the undulated or zigzag direction, (shown in Fig. 1,) and thus holding the 70 cable solidly, and yet permitting it to wind or unwind as the pulley turns. The traction is thus greatly increased, and an elevator thus constructed is capable of raising enough hods continuously to supply the demand for materials made by the high buildings now usual in 75 large cities. The wire cables pass around these pulleys and over and around two plain pulleys, J J, similarly located at the proper height upon a shaft provided with suitable bearings supported by the tubular frame A' A'. The cables are connected by parallel horizontal bars arranged at such distances apart as to support the bowl and lower part of the shank of the hod, as shown in Fig. 2. These bars are 80 fastened to the cables by ordinary clips and bolts, and should be made to stand out from the cables, by means of a small suitable block between the bar and the cable, sufficiently to pass over the flanges of the pulleys. Each 85 bar has upon each edge, as shown in Fig. 1, near and upon each side of its center, two projections, to cause the hod-bowl to center upon the bar and there retain its seat. These projections may be continued on the face of the 90 bar, to engage the hod-shank. The cables are tied together in the usual manner.

In the angular bottom of the hod-bowl, near its open end, is let a suitable notch, preferably lined with metal, and shown at e in Fig. 3, to 95 engage the edge of the bar, as shown in Fig. 4, between the projections aforesaid and pre-

vent the hod falling from its seat thereon. Full hods are elevated and empty hods returned in the usual manner, sufficiently indicated in the drawings and known in the art.

5. To secure greater adjustability, and to increase the tension of the cables by the weight of the gearing, the shafts, connected by the castings aforesaid and carrying the actuating or driving gearing and pulleys, are suspended in and by the cables, and any greater tension needed is given by the set-screws E E.

I also construct and use, as shown in Fig. 1, a metallic tubular handle, M, radially adjustable about the shaft as a center, to provide 15 greater or less leverage, according to the load being elevated, and fixed at the desired leverage by means of the set-screw N.

Having thus fully and sufficiently described my invention, I claim as new and desire to secure by Letters Patent—

1. A hod-elevating apparatus having metallic tubular frames, constructed and arranged substantially as specified.

2. A hod-elevating apparatus having actuating or driving pulleys with sufficiently deep circumferential grooves, presenting alternate

projections and preferably corresponding recessions opposite on each cheek, whereby an undulating channel is formed, as and for the purpose substantially as specified.

30

3. A hod-elevating apparatus having a handle radially adjustable about the shaft as a center, to provide greater or less leverage, substantially as specified.

35

4. A hod-elevating apparatus having a double ratchet-wheel presenting circumferentially two parallel series or sets of teeth pointing in opposite directions, and each set provided with a pawl working in its respective path, in the manner and for the purpose substantially as 40 specified.

45

5. A metallic-lined notch in the angular bottom of a hod-bowl, near the open end thereof, in combination with a bar connecting two cables, and having on its edges, near and on each side of its center, two projections, as and for the purpose substantially as specified.
